UNITED STATES PATENT OFFICE.

HENRY FUEHRER, OF HAZLETON, PENNSYLVANIA.

COMBINED REINFORCE AND MOLD-SUPPORT FOR CONCRETE STRUCTURES.

1,097,796.

Specification of Letters Patent.

Patented May 26, 1914.

Application filed April 4, 1912. Serial No. 688,423.

To all whom it may concern:

Be it known that I, HENRY FUEHRER, a citizen of the United States, residing at Hazleton, in the county of Luzerne and State of Pennsylvania, have invented certain new and useful Improvements in Combined Reinforces and Mold-Supports for Concrete Structures; and I do declare the following to be a full, clear, and exact description of the invention, such as will enable others skilled in the art to which it appertains to make and use the same.

This invention relates to a combined anchor or reinforce and mold support for concrete structures.

The object of the invention is to provide means for cheaply and strongly constructing concrete or cement walls or foundations and by the use of which the cement worker can make his own mold or form. No studs are necessary to brace the forms, much less lumber is required than in the old way, and no skilled labor is required after the first course has been laid.

Another object is to provide an equalizing anchor of this character which will automatically plumb the wall and which will remain in the wall and serve as a reinforcement thereby greatly strengthening the wall.

This invention also comprehends details of construction which, together with the features above specified, will be better understood by reference to the drawings, in which—

Figure 1 represents a front elevation of a cement wall embodying this invention and in which some of the mold boards have been removed showing the completed wall and others remaining in position awaiting the setting of the cement. Fig. 2 is a transverse vertical section on the line 2—2 of Fig. 1. Fig. 3 is an enlarged detail of one of the anchors. Fig. 4 is a detail perspective view showing the crossing of the two elements forming the anchor and the method of their engagement. Fig. 5 is an end elevation of the anchor shown in Fig. 3. Fig. 6 is an enlarged detail perspective view of the foot of one of the anchors. Fig. 7 is an enlarged detail perspective view of the top grab or mold engaging member of the anchor. Fig. 8 is a detail perspective view of a slightly modified form showing locking means for the anchor.

In the construction of a cement or concrete wall or other structure embodying this

invention a plurality of anchors such as are shown in Fig. 3, are employed for reinforcing the wall and for holding the molds or forms in operative position during the construction of the wall, (see Figs. 1 and 2). Each of these anchors 1 comprises two bars or members 2 and 3 which detachably engage each other and are interchangeable, being each composed of soft steel known as "band iron" which is preferably about three-fourths of an inch wide by one-eighth of an inch thick. These members 2 and 3 conform in size to the thickness of the wall or the depth of the boards with which they are to be used, and are each provided in one edge midway the length thereof with a notch 4, the notch in one member being formed in its lower edge and that in the other member in its upper edge to adapt them to engage to form an interlocking connection as shown in Fig. 4. It will thus be obvious that this means of connection provides for the ready separation and connection of the anchor bars to permit them to be interchanged when desired. One end of each of these bars is provided with a foot 5 adapted to engage the upper edge of one board of the mold and the lower edge of the board next above it, as shown clearly in Figs. 1 and 3. This foot 5 is formed by shearing, punching and bending one end of the bar to form depending prongs or lugs 6 and 7 spaced a suitable distance to span the edge of a board and its strengthening cleat to which the anchor is to be applied, or rather in connection with which it is to be used. The depending prong 7 at the terminal of the bar, is preferably formed by shearing the bar diagonally from one edge inward, as shown in Fig. 6, and is bent downwardly the larger portion of said terminal, being bent upwardly to form a stop or lug 8 for engaging the outer face of the lower edge of the board next above to hold said board against outward movement. The prong 6 is formed by striking out a tongue from said bar intermediately of the width thereof, which is bent downwardly to form said prong 6, and which leaves a weakened portion at the base of said prong for a purpose to be described. The body of the bar is bent at an angle at the base of said prong 6 to conform to the measurements of the boards used in forming the mold and of the wall. The other end of each bar 2 and 3 is provided with a board

engaging member herein termed "the head" and which is designed to engage the upper edge of the board at the opposite side of the mold or form from that engaged by the 5 foot of said bar, and said board being disposed in a plane above that engaged by the foot of the bar.

The head 9 of each bar is formed by bending the terminal of the bar at the head end 10 laterally in a plane at right angles to form a prong 11 for engaging the outer face of the upper edge of the board to which it is applied for holding said board against outward movement. Spaced inwardly from 15 said prong 11 are two prongs 12 and 13 extending in opposite directions and formed by striking out tongues from opposite edges of the bar and bending one in one direction and the other in the other direction. The 20 prong 12 extends in a plane parallel with the prong 11 and engages the inner face of the upper edge of the board engaged by the prong 11. The prong 13 is designed to engage the inner face of the lower edge of the 25 board next above in the same side of the mold as is clearly shown in Figs. 1 and 3. These bars 2 and 3 form when assembled an X-shaped anchor having laterally extending board engaging members at the terminals of 30 the arms thereof, the feet of the two bars being arranged in transverse alinement and the heads of said bars in transverse alinement, and the head of one bar alines with the foot of the other, the head and foot of 35 each bar being arranged diagonally in relation to the mold and designed to engage boards at opposite sides of the mold and in different planes. In the use of this improved anchor and mold support a layer of 40 concrete or cement is first laid in a concavity such as a ditch upon which the wall is to be erected. This layer is placed without forms and is accurately leveled. After it has sufficiently set or hardened the wall is erected 45 thereon in which this anchor is employed, the necessary number of boards for forming the mold having been first obtained. These boards are preferably of hemlock and of the proper width and thickness being pro- 50 vided with the usual cleats for preventing the boards from warping or splitting. Two boards are first stood on edge on the exact location for the wall to be built. Then the equalizing anchors herein described and 55 shown are placed proper distances apart after bending back the prongs on the feet of the anchors, or if the concrete is not set too hard they may be driven thereinto. A board as wide as the wall is to be thick is then 60 placed between the boards set on edge and serves to hold said vertical boards in properly spaced relation. This form or mold so constructed is then filled with cement or concrete and the next day or when 65 said first mentioned course has become suit-

ably hardened, the mold for another course is laid by mounting the desired number of anchors on the upper edge of the boards of the mold of the first course, the feet of said anchors having their depending prongs 70 fitted tightly over the board and its cleat, said anchors being set above and beside the anchors of the course below. The feet of the anchors fit the boards sufficiently tight to hold said anchors in position ready to 75 receive the boards for the next mold, which may be readily placed in position by lifting the head members of the anchors. After the boards are properly positioned the heads of the anchors are forced down over their 80 upper edges with the prongs 11 and 12 thereof engaging opposite faces of said boards. The prong 11 of the head of one bar of each anchor and the prong 8 of the foot of the other bar of said anchor hold the board 85 against being forced outward, and the prong 12 of the head of said anchor and the prong 13 of the anchor below prevent said board from moving inward. The mold thus formed is then filled with cement which 90 when hardened has another course built thereon in a similar manner, and so on until the desired height of the wall has been reached.

After the cement of the lower courses has 95 hardened sufficiently the mold boards are removed and employed in forming the other molds for the succeeding courses. These boards are removed by bending back the prongs 8 and 11 on the foot and head of 100 the vertically alined anchor members.

After the boards have been removed the ends of the anchors project beyond the outer face of the wall and they are removed preferably by bending them back and forth by 105 a pair of pliers, which causes them to break off at the points marked 14 in Fig. 2, these parts having been weakened by the slot which is formed in stamping out the prong 6 of the feet and the prongs 12 and 13 of 110 the head, these weakened points being located inside the outer face of the wall. After the prongs have been broken off the recesses left thereby are cemented over, making practically a smooth surfaced wall and 115 completely covering the anchors thus preventing rust stain on the surface of the well.

In Fig. 8 a modified form is shown in which an auxiliary reinforcement in the form of a locking bar or key 15 for the 120 anchors is arranged vertically of the structure and passes under one member of one anchor and over the other member of the other anchor, as shown clearly in Fig. 8, thereby forcing said members into locking 125 engagement at their intersecting points and holding them in this position. This bar 15 in connection with the anchor forms a fork in which is disposed a longitudinally arranged auxiliary reinforcing bar or rod 16. 130

This rod 16 is supported by the fork formed as above described before the cement is placed in the mold and after the cement is poured and hardened, said rod is held thereby and serves as a horizontal reinforce therefor.

I claim as my invention:

- 5 1. A mold support for concrete structures comprising detachably connected members, each having a head and a foot provided with mold engaging prongs, and an auxiliary member arranged to lock said members in engaged position.
- 10 2. A mold support for concrete structures comprising members intersecting each other and having mold board engaging elements extending at an angle from each end thereof, and interlocking notches intermediately

of their ends and a locking bar engaged with said members to lock them together at their 20 points of intersection.

3. A mold support for concrete structures comprising two members crossing each other intermediately of their ends and provided with interlocking notches at their points of 25 intersection, said members having their free ends provided with mold board engaging elements, and a bar engaged with said members to lock them together.

In testimony whereof I have hereunto set 30 my hand in presence of two subscribing witnesses.

HENRY FUEHRER.
